UNITED STATES PATENT OFFICE.

ALBERT W. PEARSALL, OF LOWELL, MASSACHUSETTS, ASSIGNOR TO THE LAMSON COMPANY, OF BOSTON, MASSACHUSETTS, A CORPORATION OF NEW JERSEY.

DESPATCH AND DISTRIBUTING SYSTEM.

1,256,037.

Specification of Letters Patent. Patented Feb. 12, 1918.

Application filed June 21, 1913. Serial No. 774,966.

To all whom it may concern:

Be it known that I, ALBERT W. PEARSALL, a citizen of the United States, residing at Lowell, in the county of Middlesex and State 5 of Massachusetts, have invented certain new and useful Improvements in Despatch and Distributing Systems, of which the following is a specification.

This invention relates more particularly 10 to pneumatic despatch tube systems and especially to a combination of such systems with automatic means for removing and selectively receiving and distributing carriers delivered through the transmission tubes.

15 The carriers which may thus be automatically handled may contain parts for machine assembling; powder, etc., for the manufacture of cartridges; checks and money, or checks alone, covering cash or credit transactions, etc.

In certain cases the automatic selecting and distributing means may receive carriers initially propelled by other than fluid pressure and I hence desire not to be limited to 20 pneumatic despatch systems except when the claims appended hereto specifically so indicate.

The combinations of elements hereinafter described are, however, of special value in 25 pneumatic despatch systems and the preferred embodiment of my invention herein disclosed accordingly pertains to such a system.

One of the objects of the present invention 30 is to provide a receiver for pneumatic despatch tube carriers, after their delivery from any type of receiving terminal that will permit of their reception without injury, automatically and positively retaining 35 them in a position to be consecutively and automatically removed by suitable mechanism.

An important feature of the invention is 40 the provision of means for automatically removing the carriers so retained in said receivers, for separating said carriers into groups or classes and distributing them at

determined points in such manner that an individual, cashier, authorizer or other operative for, if desired, each of said classes, may 50 handle them without other effort, mental or manual, than the removal of said carriers from determined repositories, together, of course, if desired, with an inspection of the contents thereof.

55 These and other objects of my invention will be hereinafter referred to and the novel elements and combinations of elements whereby said objects may be attained will be more particularly set forth in said claims.

60 Referring to the drawings, which form a part hereof and in which like reference characters designate like parts throughout the several views:—I have exemplified, as previously stated, a preferred embodiment 65 of my invention, but I am aware that various changes and modifications may be made herein without departing from the spirit of the invention, and I hence desire to be limited only by the scope of said claims.

70 In the drawings:—

75 Figure 1— is a front elevation of a pneumatic despatch station, showing groups of despatch tube terminals and associated therewith, receiving, separating and distributing apparatus adapted to effect the objects set forth.

80 Fig. 2— is a section of the apparatus shown in Fig. 1; the section being taken on line II—II of said figure.

85 Fig. 3— is an enlarged detail of portions of the collecting and distributing apparatus shown in Fig. 1.

Fig. 4— is a detail front view of a fragment of the apparatus shown in Fig. 3.

85 Fig. 5— is, correspondingly, a detail front elevation of the upper portion of said apparatus shown in Fig. 3, and

90 Fig. 6— is a fragmentary plan view of sections of the belts used in the distributing apparatus; said view further illustrating the differences between the carriers to be assorted.

The despatch tubes incoming to said sta-

tion have been designated 1, and the outgoing tubes, 2.

A drum 3, assuming the system to be of the vacuum type, is in communication with the tubes 4 leading into the tubes 1 in a known manner; the receiving terminals 5 being also of any suitable construction; the carriers emerging from the tubes 1 thereinto and passing thence to the tubes or receptacles 6, which, together with the casings 7 at the lower extremities of these tubes, constitute the receivers proper for the carriers in the present instance.

The lower extremities of the casings 7 are provided with curved movable members 8, which may be pivotally connected, as at 9, to the casings 7 and which are so shaped that the carriers may descend through the casings 7 and will have their path of movement changed before coming to rest, so that said carriers will repose in said members 8 at an angle approximating 45°.

The carriers 10 or 10', as the case may be, are held temporarily in place in the members 8 by means of retaining elements 11 pivoted to the members 8 at 9'. These elements preferably are made of light rods bent, as indicated in Figs. 3 and 5, to form loops; the transverse portion of each lower loop being adapted for engagement with the upper portion of the front end or felt head of the carrier when the latter descends into the corresponding member 8 and thereby serving to retain said carrier in its inclined position above referred to.

This lower loop is so shaped, also, as to enable this transverse portion thereof to clear the projections 12 which are provided upon the ends of the carriers 10, while the upper loop 11' of the element 11 extends up, preferably into a slot in a carrier latching member 13.

As shown in Fig. 5, the members 8 are slotted upon the respective sides thereof at their lower extremities as at 8', to permit of the passage therethrough of hooks 14, which project upwardly from preferably metal sections 15 secured to the belts 16 and 16'. As indicated in Fig. 3, the transverse portion of each loop is also up-bent at each side thereof, as at 17, to clear these hooks and, since the loops are also provided with parts 18 which engage notches 18' at the lower extremities of the members 8, said hooks will always pass freely beneath the loops or elements 11 without disturbing them.

It should be noted in this connection that the downward swing or movement of the members 8 is also limited by the engagement of the portions 19 thereof with the respective lower extremities 19' of the casings 7.

The plates or sections 15 also have up-

wardly extending therefrom fingers 20, the upper ends of which are preferably bent in, as at 20' to adapt them for engagement with the side portions of the elements 11, as indicated in the left hand portion of Fig. 5.

As the belts 16-16', upon which the parts 14, 15 and 20 are mounted, are driven in the direction of the arrow indicated in Fig. 5, the transverse portions 20' engage and swing the respective lower loops of the element 11 laterally and upwardly so that they may each clear the end of the carrier which may, at such time, happen to be retained therein.

Immediately thereafter, or substantially coincidentally with this release of the carrier, the corresponding pair of hooks 14, which have passed through the slots 8' in the walls of the members 8, engage the rear annular surface 12' of the lower or forward head of said carrier, and aided by gravity, pull it out of its holding member 8, so that the carrier is free to fall downwardly onto the belt; the curved tip 22 of the retaining loop riding on the shell of the carrier and preventing the loop from catching on the rear felt buffer or head; which action, would of course, interfere with the removal of the carrier. At the same time the upper portion 11' of the element 11 is swung inwardly and rocks the latching or holding member 13 into position to retain a succeeding carrier, if such a carrier should be in the receiver immediately back of the one being removed; the point 13' of the hook of member 13 being then disposed at the end of its inward movement; as indicated by dotted lines in the left hand portion of Fig. 5.

As indicated in Figs. 4 and 6, the forward head of the carrier will be in advance of the hooks 14, and is received into a recess 23 in the plate 15; the belt being correspondingly apertured beneath the plate 15 to permit of the entrance of the carriers thereinto. This aperture in the belt is extended rearwardly, but of somewhat less width, so as to accommodate the body of the carrier; while said aperture is again enlarged as at 24, to receive freely the rear head of the carrier.

The plate 15 is preferably relatively narrow in the direction of the length of the belt and is flexibly connected or joined to short strips or links 25, which may also be of metal; the rear extremities of these strips being correspondingly connected to a plate 15' of substantially the same form as the plate 15.

By virtue of this jointed construction the metal or relatively non-flexible parts, disposed around the opening in the belt which receive the carrier, are able to accommodate themselves to the passage of the portion of the belt to which they are attached around a pulley. At the same time, while the belt is

obviously weakened by aperturing it for the reception of carriers, the securely linked or jointed metallic plates 15—15' secured thereto prevent rupture or undue stretching 5 at this point. It may be noted that the plates 15—15' may be secured to the belt by rivets 26, or in any other suitable manner.

The belts 16—16' are preferably disposed side by side, passing around idlers 27 and a 10 pulley 27'; the latter being fixedly connected to its shaft 28 and driven by an electric motor 29 and belt 30, as indicated in Fig. 1.

By reason of the disposition of the idlers and pulleys 27—27', the circuit of each belt 15 is substantially rectangular, and normally only that portion of the belt traversing the upper side of the rectangular course is utilized.

Referring now more particularly to Figs. 20 4, 5 and 6, it will be noted that the carriers designated 10', since they have no projections 12 at the ends thereof, are free to drop through the aperture in the belt into which they are deposited, until they rest upon the 25 smooth bottom 31 of the channel-way in which the belt travels and are drawn along by said belt until they encounter a chute 32 (or 32', as the case may be) whereupon they drop completely through the belt into said 30 chute.

On the other hand, those carriers designated 10, which are provided with extensions or projections 12, cannot fall through the belt, since said projections engage the 35 plates 15 and 15' respectively and will pass over the chute 32 or 32' and will not be deposited from the belt until the portion of the latter into which they extend encounters the idler 27, toward which it is being moved. 40 Thereupon, since the belt is drawn downwardly away from the carrier; the heads of the latter will only rest upon the said bottom 31 until the forward head of the carrier is free to enter a chute 33, correspondingly to the belt 16, or chute 33', in line with belt 16', as the case may be (see Fig. 1).

In this way one class of carriers may be intermingled with a second class in the dispatching tubes; and the receivers and the 50 portions of the tube delivering thereto will contain, possibly, a heterogeneous collection of carriers which are successively removed from each of the respective receivers by the elements 20 and hooks 14, when the aperture 55 in the belt, corresponding to the pair of hooks, is unoccupied by a previously introduced carrier.

Assuming, however, that a carrier has been delivered from the left hand receiver in 60 Fig. 1 to the corresponding belt:—when said carrier encounters the pivotal member 8 of the next receiver it merely swings the latter, together with the carrier which may be

therein and the loop 11 pertaining thereto, up out of the way, so that the trips or fingers 20 immediately adjacent cannot engage the element 11 of this next receiver. 65

Immediately thereafter the member 8 of said receiver drops back into its normal position, so that thereafter the first unoccupied 70 pair of hooks which pass therethrough will remove the lowermost carrier in such receiver in the manner above described.

Accordingly, carriers delivered to the receivers will be successively removed practically in the order of their arrival at the station; and will be not only conveyed to points where they may be inspected or otherwise disposed of, but will be sorted according to their respective classes. 75

If desired, the belt which conveys carriers from the more remote group of terminals may have its speed proportioned to the belt receiving from the terminal group nearer the discharge hoppers 33—33', so that the 80 average time of transit from the terminal group A to its hopper 33 will equal that from group B to its hopper 33'.

Let us assume that the carriers designated 10' are cash carriers and that those designated 10 are credit carriers. It is evident that all cash carriers will be deposited in one of the chutes 32—32', there being, in the present instance, two of these chutes, one for each of the belts. Correspondingly, all 90 credit carriers will be delivered to one or the other of the chutes or hoppers 33—33', according to which belt they are being conveyed by. 95

I have shown by way of exemplification 100 but two terminals in a group, but in practice, of course, a considerable number of terminals may deliver at a given point in a station. Conveniently spaced from a first group A there may be a second group B; and one 105 belt 16 will be disposed to receive carriers from the terminals of group A, while a second and preferably parallel belt 16' will receive carriers from the terminals in group B. In Fig. 2, for convenience of illustration, the terminals in group A have been omitted. The chutes or hoppers 32 and 32', which 110 respectively receive carriers 10' from belts 16 and 16' are preferably adjacently disposed so that the operative stationed at this point 115 need at no time reach any considerable distance.

Correspondingly, the chutes 33 and 33' which receive the carriers 10 from the respective belts may also be disposed adjacent to each other; and on the above assumption that the carriers 10' are for cash and carriers 10, for credit, the credit desk will be located at this point, while the cash desk will be adjacent to the chutes 32—32'. 120

The number of belts used will depend 125

upon the extent of the installation, it being 5
inadvisable to have any one belt receive carriers
from an excessively large number of terminals,
owing to the fact that the terminals nearest
the approaching openings in the belt would be given
preference over subsequent terminals in the group.

In stores, for example, it becomes of the
utmost importance to provide prompt service
10 for credit customers who expect to merely
present a check or other identifying token
and to receive their goods without delay.
For this reason credit transactions are given
preference over cash transactions, and at-
tempts have been made to meet this demand
15 by relaying the credit carriers, delivering all
carriers, cash and credit, to one desk and by
having an operative stationed at this point to
select the credit carriers from the mass and
20 forward them through a separate tube, or
in some other suitable manner, to the credit
desk. This necessitates the employment, fre-
quently, of an additional operative, and ren-
ders the prompt transmission of credit car-
25 riers subject to the human equation.

Furthermore, when the cash and credit
carriers are intermixed and are delivered to
the usual shelf or extension of the terminal
tube, provided with an opening near the
30 lower extremity thereto of sufficient size to
permit of the removal of but one carrier at a
time, the credit carriers will be held up pend-
ing the removal of preceding cash carriers
and, frequently, even the disposition of the
35 contents of such cash carriers.

The system herein described obviously
does away with all of these objectionable fea-
tures and insures a prompt transmission of
credit carriers to the credit desk, substan-
40 tially in the order in which they have been
delivered to the station; while at the same
time automatically sorting the cash carriers
from the credit carriers and delivering these
45 in practically sequential order to the opera-
tive at the cash desk.

The remaining parts of the system need
not be particularly referred to, since they
may be of any known description; and it
will suffice to say, therefore, that the parts
50 designated 34 are the despatching terminals
of the system, while the hoppers 32-32' and
33-33' respectively deliver to carrier re-
ceiving shelves or repositories 35-35' and
36-36' of a known construction; each of
55 these shelves being provided with the usual
aperture 37 adjacent the lower extremity
thereof, through which the carriers may be
removed.

Having thus described my invention what
60 I claim is:-

1. The combination of a pneumatic des-
patch tube system having a terminal, with
a mechanism for automatically removing

carriers from said system after their arrival
at said terminal, said mechanism having 65
carrier head engaging devices adapted to
co-act with said carriers and co-acting
means to distribute the latter selectively in
accordance with the classes of said carriers.

2. The combination of a pneumatic des-
patch tube system having a terminal, with
a continuously driven mechanism for auto-
matically removing carriers from said sys-
tem after their arrival at said terminal, said 75
mechanism having devices adapted to co-act
with said carriers and coacting means to
distribute the latter selectively in accord-
ance with the classes of said carriers.

3. The combination of a pneumatic des-
patch tube system having a terminal pro-
vided with a receiver having means for
holding a carrier delivered to said receiver
therein, mechanism for releasing said car-
rier from said receiver and conveying it
away therefrom, said mechanism having 85
parts adapted to selectively receive the re-
leased carriers in accordance with the classes
of said carriers and co-acting means for dis-
tributing said carriers according to their re-
spective classes.

4. The combination of a pneumatic des-
patch tube apparatus having a terminal pro-
vided with a receiver in which the carriers
delivered to said terminal normally come
to rest, means for effecting a dislodgment 95
of said carriers from said receiver, mech-
anism for receiving and supporting the dis-
lodged carriers, said mechanism adapted to
hold or support one class of said carriers
differently from another class, and separate 100
means for receiving the respective differ-
ently supported carriers.

5. The combination of a pneumatic des-
patch tube apparatus having a terminal pro-
vided with a receiver in which the carriers 105
delivered to said terminal normally come
to rest, means for effecting a dislodgment
of said carriers from said receiver, co-acting
mechanism for receiving and supporting the
dislodged carriers, and co-acting means for 110
receiving carriers from said mechanism in
accordance with the classes to which such
carriers pertain.

6. The combination of a pneumatic des-
patch tube apparatus having a terminal pro-
vided with a receiver in which the carriers
delivered to said terminal normally come
to rest, means for effecting a dislodgment 115
of said carriers from said receiver, co-acting
conveying mechanism for receiving and sup-
porting the dislodged carriers, and co-acting
means for receiving carriers from said mech-
anism in accordance with the classes to
which such carriers pertain.

7. The combination of a pneumatic des-
patch tube apparatus having a terminal pro-

vided with a receiver in which the carriers delivered to said terminal normally come to rest, means for effecting a dislodgment of said carriers from said receiver, co-acting 5 conveying mechanism for receiving and supporting the dislodged carriers, and co-acting means for receiving carriers from said mechanism in accordance with the classes to which such carriers pertain, carriers 10 of different classes conveyed by said mechanism traversing a determined path to a determined point, said conveying mechanism having parts adapted to support carriers in one class while leaving carriers of another class substantially unsupported at 15 said point.

8. The combination of a pneumatic despatch tube apparatus having a terminal provided with a receiver into which the carriers 20 are delivered, co-acting power driven conveying mechanism for receiving carriers pertaining to a plurality of classes from said receiver, said mechanism having carrier holding parts, and co-acting means for 25 receiving carriers from said mechanism in accordance with the classes to which such carriers pertain, carriers of different classes conveyed by said mechanism traversing a determined path to a determined point, said 30 carrier holding parts adapted to support carriers in one class but to release carriers of another class at said point.

9. The combination of a pneumatic despatch tube apparatus having a plurality of terminals and transmission tubes adapted to deliver carriers of different classes to said terminals, with a mechanism common to said tubes and terminals for automatically receiving and conveying carriers of 35 said different classes away from said terminals, said mechanism provided with means for distributing carriers according to their respective classes.

10. The combination of a pneumatic despatch tube apparatus having a plurality of terminals and transmission tubes adapted to deliver carriers of different classes to said terminals, a mechanism common to said tubes and terminals for automatically receiving and conveying carriers of said different classes away from said terminals, said mechanism provided with means for automatically assorting and distributing carriers according to their respective classes.

55 11. The combination of a pneumatic despatch tube through which carriers of different classes are propelled indiscriminately, with a combined assorting and distributing mechanism adapted to receive said carriers therefrom, said mechanism having provisions for selectively supporting said carriers and unloading them according to 60 classes at different points along a deter-

mined path traversed by parts of said mechanism, and means for driving said mechanism.

12. The combination of a pneumatic despatch tube through which carriers of different classes are propelled indiscriminately, with a combined assorting and distributing mechanism adapted to receive and selectively support said carriers, said mechanism being extraneous to said tube and adapted to receive carriers of all of said classes successively therefrom, and means for driving 75 said mechanism.

13. The combination of a pneumatic despatch tube through which carriers of different classes are propelled indiscriminately, with a combined assorting and distributing mechanism adapted to receive said carriers therefrom, said mechanism including a flexible element provided with means for variably engaging pneumatic despatch carriers according to the class thereof, and means for driving said flexible element.

14. The combination of a plurality of pneumatic despatch tubes through which carriers of different classes are propelled indiscriminately, with a combined assorting and distributing mechanism common to said plurality of tubes and adapted to receive said carriers therefrom, said mechanism including a flexible element adapted to move said carriers away from said tubes, said mechanism including means for supporting said carriers, during their conveyance by said flexible element, for variable distances, carriers of one class being freed from the action of said flexible element before carriers of a second class.

15. The combination of a pneumatic despatch tube provided with a receiver to which carriers of different classes indiscriminately traversing said tube are delivered, with an assorting mechanism including a flexible element provided with carrier engaging parts and spaced means for effecting the removal from said receiver of said carriers and the disposition of the latter selectively with respect to said carrier engaging parts.

16. The combination of a pneumatic despatch tube system having a terminal provided with a receiving part, extraneous power driven means for removing carriers successively from said receiving part, and means for retaining carriers in said receiving part until removed by said power driven means, said receiving part adapted to hold a carrier about to be removed therefrom at an angle to the horizontal.

17. The combination of a pneumatic despatch tube system having a terminal provided with a receiving part, extraneous power driven means for removing carriers

successively from said receiving part, and means for retaining carriers in said receiving part until removed by said power driven means, said receiving part adapted to hold 5 a carrier about to be removed therefrom at an angle to the horizontal and to deliver said carrier endwise thereof to said power driven means.

18. The combination of a pneumatic des- 10 patch tube system having a terminal provided with a receiving part, extraneous power driven means for removing carriers successively from said receiving part, and means for retaining carriers in said receiving part until removed by said power driven means, said receiving part adapted to deliver carriers endwise thereof to said power driven means.

19. The combination of a pneumatic des- 20 patch tube through which carriers of different classes are propelled indiscriminately, with a combined assorting and distributing device including a moving flexible element provided with apertured parts into which 25 said carriers may enter, said device having means for retaining said carriers in said apertured parts for a determined distance from the point of entry thereinto and for releasing carriers of only one of said classes 30 after said distance has been traversed.

20. The combination of a carrier despatch system proper having a terminal part, with a mechanism having means for automatically removing carriers from said system 35 after their arrival at said part, said mechanism having continuously driven provisions adapted to co-act with said carriers and means, coacting with said mechanism, to effect a distribution of said carriers selectively at points outside of said system in 40 accordance with the classes of said carriers.

21. The combination of a carrier despatch system having a terminal receiver, with a mechanism having means for automatically 45 removing carriers from said receiver, said mechanism including a continuously driven flexible element movable longitudinally thereof and provided with parts adapted to co-act with said carriers and means, co- 50 acting with said flexible element, to effect a distribution of said carriers selectively in accordance with the classes of said carriers.

22. The combination of a carrier despatch system having a terminal receiver, with a 55 normally continuously operating mechanism to which carriers of different classes are delivered from said receiver, said mechanism provided with selective supports for said carriers and with means to co-act with said supports for assorting and distributing said carriers according to the classes thereof.

23. The combination of a carrier despatch system having a terminal receiver, with a

mechanism to which carriers of different classes are delivered from said receiver, said 65 mechanism including a flexible conveying element provided with jointed supporting parts for some at least of said carriers and a revoluble member around which said element passes, said mechanism adapted to unload carriers unsupported by said parts at a determined point, and to unload other carriers supported by said parts at another point.

24. The combination of a carrier despatch- 75 ing system having a terminal receiver, with a mechanism to which carriers of different classes are delivered from said receiver, said mechanism including a conveying element having parts adapted to support carriers 80 of one class and to leave carriers of a second class unsupported thereby, means for independently supporting said carriers of said second class for only a determined distance from said receiver, and means for separately dislodging said carriers of said first 85 class from said supporting parts.

25. The combination of a carrier des- 90 patching system having a terminal re- ceiver, with a mechanism to which carriers 95 of different classes are delivered from said receiver, said mechanism including an ap- 100 pertured conveying element having parts adapt- ed to support carriers of one class and to leave carriers of a second class unsupported in the apertures of said element, means for independently supporting said carriers of the second class for only a determined distance from said receiver, and means for separately dislodging said carriers of said first class from said supporting parts.

26. The combination of a carrier despatch- 105 ing system having a plurality of terminals proper, with apparatus to which carriers are delivered from said terminals, said ap- 110 paratus having a conveying element common to said terminals and provided with means for engaging said carriers to effect movement thereof away from said terminals, said apparatus having yielding means for permitting the safe passage of a carrier 115 being conveyed by said element, past a carrier-laden terminal located adjacent the path of movement of said carrier.

27. The combination of a carrier despatch- 115 ing system having a plurality of terminals proper, with apparatus for collecting carriers from said terminals, said apparatus comprising yieldingly mounted receivers to which said carriers are delivered from said terminals and a carrier conveying element common to said terminals and receivers, the yielding mounting of said receivers permitting of the safe passage therest of pre- 120 viously loaded carriers.

28. The combination of a carrier despatch-

ing system having a plurality of terminals proper, with apparatus for collecting carriers from said terminals, said apparatus comprising yieldingly mounted receivers to 5 which said carriers are delivered from said terminals and a carrier conveying element common to said terminals and receivers, the yielding mounting of said receivers permitting of the safe passage therewith of previously loaded carriers, said previously loaded carriers adapted to lift subsequently 10 encountered receivers and pass thereunder.

29. The combination of a carrier despatching system having a plurality of terminals proper, with apparatus for collecting carriers from said terminals, said apparatus comprising yielding pivotally mounted receivers to which said carriers are delivered from said terminals and a carrier conveying

element common to said terminals and receivers, the yielding mounting of said receivers permitting of the safe passage therewith of previously loaded carriers.

30. The combination of a carrier despatching system, a receiver for carriers traversing said system, a conveying element movable past said receiver, a part carried by said element for engaging carriers to withdraw them from said receiver, said receiver being apertured to permit said part to pass therethrough, and means for driving said conveying element.

In testimony whereof I have affixed my signature, in the presence of two witnesses.

ALBERT W. PEARSALL.
